United States Patent Office

Des. 205,557
Patented August 16, 1966

205,557

CAP FOR A PRESSURIZED CAN

Ronald B. White, Bournemouth, England, assignor to
Edward Webster Ltd., Bournemouth, England, a British
company

Filed Mar. 30, 1965, Ser. No. 84,509

Term of patent 14 years

Claims priority, application Great Britain, Sept. 30, 1964,
918,407/64

(Cl. D58—26)

FIG.1.

5 —

5 —

FIG.2.

FIG.3.

FIG.4.

FIG.5.

FIG.6.

FIG. 1 is a front elevational view of a cap for a pressurized can showing my new design;

FIG. 2 is a rear elevational view;

FIG. 3 is a side elevational view;

FIG. 4 is a top plan view;

FIG. 5 is a sectional view taken on the line 5—5 of FIG. 1; and

FIG. 6 is a bottom plan view thereof.

I claim:

The ornamental design for a cap for a pressurized can, substantially as shown and described.
